[57] CLAIM

The ornamental design for a combined optical scanner and base, as shown and described.

DESCRIPTION

FIG. 1 is a front perspective view of a combined optical scanner and base according to the present invention;

FIG. 2 is a top plan view thereof;

FIG. 3 is a front elevational view thereof;

FIG. 4 is a rear elevational view thereof;

FIG. 5 is a left side elevational view thereof; the right side being a mirror image;

FIG. 6 is a perspective view of the optical scanner of FIG. 1;

FIG. 7 is a front elevational view of the optical scanner of FIG. 6;

FIG. 8 is a top plan view of the optical scanner of FIG. 6;

FIG. 9 is a right side elevational view of the optical scanner of FIG. 6., the left side being a mirror image;

FIG. 10 is a rear elevational view of the optical scanner of FIG. 6;

FIG. 11 is a bottom plan view of the optical scanner of FIG. 6;

FIG. 12 is a perspective view of the base of FIG. 1;

FIG. 13 is a top plan view of the base of FIG. 12;

FIG. 14 is a rear elevational view of the base of FIG. 12;

FIG. 15 is a right side elevational view of the base of FIG. 12, the left side being a mirror image;

FIG. 16 is a front elevational view of the base of FIG. 12; and,

FIG. 17 is a bottom plan view of the base of FIG. 12.

The optical scanner is shown separately in FIGS. 6-11, and the base is shown separately in FIGS. 12-17 for clarity of illustration.
